UNITED STATES PATENT OFFICE.

ROBERT C. HARGREAVES, OF DETROIT, MICHIGAN.

DESIGN FOR A VEHICLE TIRE.

Application filed October 3, 1925. Serial No. 15,009. Term of patent 7 years.

To all whom it may concern:

Be it known that I, ROBERT C. HARGREAVES, a citizen of the United States, residing at Detroit, in the county of Wayne and State of Michigan, have invented a new, original, and ornamental Design for Vehicle Tire, of which the following is a specification, reference being had to the accompanying drawings, forming a part thereof.

Figure 1 is a plan view of the face of the tread, and

Figure 2 shows a section along the line 2—2 of Fig. 1, and looking in the direction of the arrows.

I claim:

The ornamental design for a vehicle tire, as shown.

In testimony whereof I affix my signature.

ROBERT C. HARGREAVES.
